UNITED STATES PATENT OFFICE

PAUL P. STOCKER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

TRAIN INDICATING APPARATUS

Application filed January 16, 1930. Serial No. 421,144.

My invention relates to train indicating apparatus, and particularly to apparatus for indicating the number of trains entering a given stretch of track, and for indicating the number of such trains leaving such stretch of track.

I will describe one form of apparatus embodying my invention, and will then point out the novel features thereof in claims.

10 The accompanying drawings, Figs. 1 and 2, when placed end to end with Fig. 1 on the left, constitute a diagrammatic view showing one form of apparatus embodying my invention. Fig. 2 illustrates parts of the 15 apparatus associated with a trackway, and Fig. 1 illustrates parts of the apparatus which are grouped in some central location such, for example, as a train despatcher's office, and which are controlled by the apparatus shown in Fig. 2.

Referring to the drawings, reference characters 1 and 1^a, shown in Fig. 2, designate the track rails of a stretch M of railway track which is connected with a passing siding or 25 other auxiliary track N by means of switches J¹ and J². As indicated by the arrows, eastbound traffic, that is, traffic proceeding from left to right as shown in the drawings, moves over stretch M whereas westbound traffic 30 moves over auxiliary track N. Rails 1 and 1^a are divided by insulated joints 2 into approach sections a—A and f—F, switch sections C—A—G and D—F—H, main detector track section C—D, and auxiliary detector track section G—H. Each of these track sections is provided with a track circuit which 35 is supplied with current by a battery 3 connected across the rails adjacent one end of the section, and which includes a relay designated by the reference character R with a distinguishing exponent and connected across the rails adjacent the opposite end of the section.

40 A slow-release relay r¹ is controlled by front contacts of relays R⁵ and R⁶, and hence serves as a repeater for these two relays. A slow-release relay r² is similarly controlled by front contacts of relays R¹ and R², and hence serves as a repeater for these two relays.

45 A directional stick relay I¹ is provided

with a pick-up circuit by which it becomes energized when an eastbound train enters section D—F—H. Relay I¹ continues energized by its stick circuit while the eastbound train is moving through section D—F—H. 55 A directional stick relay I² is similarly controlled when a westbound train enters section C—A—G and while the westbound train is passing through this section.

50 A westbound arrival code control relay T¹ becomes energized when a westbound train having entered section G—H, moves out of section D—F—H. An eastbound arrival code control relay T² similarly becomes energized when an eastbound train, having entered section C—D, moves out of section C—A—G. 55

An eastbound departure code control relay Y¹ becomes energized when an eastbound train enters section D—F—H. A westbound departure code control relay Y² similarly becomes energized when a westbound train moving through section G—H enters section C—A—G. 60

65 Relays t¹ and t² are controlled by front contacts of relays T¹ and T², respectively, and therefore serve as repeaters for these two relays. Relays y¹ and y² are controlled by front contacts of relays Y¹ and Y², respectively; and therefore serve as repeaters for 70 these relays. Each of the relays t¹, t², y¹ and y² is so constructed as to be slow in lifting its contacts after becoming energized.

75 A code transmitting device E¹ is located adjacent switch J¹, and a similar code transmitting device E² is located adjacent switch J². Transmitter E¹ is so controlled by relays t¹ and T¹ that when a westbound train entering stretch N leaves section D—F—H, transmitter E¹, for a brief period of time, 80 supplies current of a given code to line conductors 8 and 9. Transmitter E² is so controlled by relays y² and Y² that when a westbound train passing through section G—H enters section C—A—G, transmitter 85 E² supplies conductors 8 and 9 with current of a second given code. Transmitter E², being also controlled by relays t² and T², supplies conductors 8 and 9 with current of a 90 third code when an eastbound train moving 95

through section C—D leaves section C—A—G. Transmitter E¹, being also controlled by relays r^4 and Y^1 , supplies conductors 8 and 9 with current of a fourth code when an eastbound train moving through section C—D enters section D—F—H.

At the despatcher's office, selectors designated by the reference characters S¹, S², S³ and S⁴, respectively, are connected across conductors 8 and 9. Each of these selectors comprises a winding 34 and a contact 35 which is controlled by winding 34 and which becomes closed when current of a code, to which the selector responds, is supplied to its winding 34. Selector S¹ is controlled by current of the first code, selector S² is controlled by current of the second code, selector S³ is controlled by current of the third code, and selector S⁴ is controlled by current of the fourth code.

An indication relay K¹ is controlled by selector S¹ when a normal contact 37^a of a polarized relay L¹ is closed. A second indication relay K² is controlled by selector S¹ when a reverse contact 37^b of polarized relay L¹ is closed and a normal contact of a second polarized relay L² is closed. A third indication relay K³ is controlled by selector S¹ when reverse contacts of relays L¹ and L² are closed and a normal contact of a third polarized relay L³ is closed. Selector S² similarly controls indication relays P¹, P² and P³ according to the position of the polar contacts of relays Q¹, Q² and Q³, respectively. Relays L¹, L² and L³ are energized in the normal or the reverse direction according as relays K¹, K² or K³, respectively, are deenergized or energized. Relays Q¹, Q² and Q³ are likewise energized in the normal or the reverse direction according as relays P¹, P² or P³, respectively, are deenergized or energized.

Relays K¹, K² and K³ control indicators, here shown as electric lamps e¹, e² and e³, respectively, which are mounted in a diagram or model *n* of track N. Similar indicators designated e⁴, e⁵, and e⁶ are mounted in the portion *m* of the diagram or model representing track M, and are controlled exactly similarly to lamps e¹, e² and e³, by means of a group of relays not shown, which are controlled by selectors S³ and S⁴ exactly similarly to the manner in which relays K, L, P and Q are controlled by selectors S¹ and S².

Having described, in general, the arrangement, location and operation of the various parts comprising my invention, I will now trace in detail the operation of the apparatus.

As shown in the drawings, all parts are in their normal condition, that is, all track sections are unoccupied, and hence all relays R are energized. With relays R⁵ and R⁶ energized, relay r^1 is energized by its circuit

passing from terminal B of a current source not shown in the drawings, through contact 4 of relay R⁶, contact 5 of relay R⁵, and the winding of relay r^1 to terminal *o* of the same source of current. Relay r^2 is also energized by its circuit passing from terminal B, through contact 6 of relay R¹, contact 7 of relay R², and the winding of relay r^2 to terminal *o*.

Relay L¹ is energized in the normal direction by its circuit passing from terminal B, through contact 40^b of relay K¹, and the normal winding or relay L¹ to terminal *o*. Relays L² and L³ are also energized in the normal direction by similar circuits controlled by contacts 40^b of relays K² and K³, respectively. Relay Q¹ is energized in the normal direction by its circuit passing from terminal B, through contact 46^b of relay P¹, and the normal winding of relay Q¹ to terminal *o*. Relays Q² and Q³ are energized in the normal direction by exactly similar circuits which are controlled by contacts 46^b of relays P² and P³, respectively.

I will now assume that a westbound train enters section F—F, reenergizing relay R⁶ which in turn deenergizes relay r^1 . With relay r^1 deenergized, relay I¹ continues deenergized when the train enters section D—F—H. When the train, after entering section G—H, moves out of section D—F—H, relay T¹ becomes energized by its circuit passing from terminal B, through contact 10 of relay R⁴, contact 11 of relay R⁵, contact 12 of relay I¹, and the winding of relay T¹ to terminal *o*. Relay T¹ upon becoming energized closes its contacts 28 and 31. With contact 28 closed, relay t¹ becomes energized by its circuit passing from terminal B, through contact 28, and the winding of relay t¹ to terminal *o*, but on account of the slow pick-up characteristic of relay t¹, contact 30 of relay t¹ remains closed for a brief period.

During this brief period, the first control circuit for code transmitter E¹ is closed, passing from terminal B, through contact 30 of relay t¹, contact 31 of relay T¹, and code transmitter E¹ to terminal *o*. During the brief period before contact 30 opens, after contact 31 of relay T¹ has closed, code transmitter E¹ supplies current of the first code to conductors 8 and 9, causing selector S¹ to close its contact 35.

Relay K¹ then becomes energized by its circuit passing from terminal B, through contact 35 of selector S¹, wire 36, contact 37^a of relay L¹, and the winding of relay K¹ to terminal *o*. When contact 30 of relay t¹ opens, code transmitter E¹ ceases supplying current of the first code to conductors 8 and 9, and hence contact 35 of selector S¹ opens, but relay K¹ continues energized by its stick circuit passing from terminal B, through contact 38 of relay P¹, contact 39 of relay K¹, 130

and the winding of relay K^1 to terminal o . Relay K^1 , upon becoming energized, causes lamp e^1 to become lighted by its circuit passing from terminal B, through contact 41 of relay K^1 , and lamp e^1 to terminal o . Relay K^1 , upon becoming energized, also completes a reverse control circuit for relay L^1 passing from terminal B, through contact 40^a of relay K^1 , and the reverse control winding of relay L^1 to terminal o . Relay L^1 then opens its contact 37^a and closes its contact 37^b.

If, now, a second westbound train follows the first train into stretch N, causing code transmitter E^1 to again supply current of the first code to conductors 8 and 9, selector S^1 again closes its contact 35, this time completing the pick-up circuit for relay K^2 passing from terminal B, through contact 35 of selector S^1 , wire 36, contact 37^b of relay L^1 , contact 37^a of relay L^2 , and the winding of relay K^2 to terminal o . Relay K^2 then continues energized by its stick circuit passing from terminal B, through contact 38 of relay P^2 , contact 39 of relay K^2 , and the winding of relay K^2 to terminal o . Relay K^2 , upon becoming energized, causes lamp e^2 to become lighted by its circuit passing from terminal B, through contact 41 of relay K^2 , and lamp e^2 to terminal o . Relay K^2 , upon becoming energized, also causes relay L^2 to be energized in the reverse direction by its reverse control circuit passing from terminal B, through contact 40^a of relay K^2 , and the reverse control winding of relay L^2 to terminal o . Relay L^2 then opens its contact 37^a and closes its contact 37^b.

If, now, a third westbound train enters stretch N, causing code transmitter E^1 to again supply current of the first code to conductors 8 and 9, selector S^1 again closes its contact 35, this time completing the pick-up circuit for relay K^3 passing from terminal B, through contact 35 of selector S^1 , wire 36, contact 37^b of relay L^1 , contact 37^b of relay L^2 , contact 37^a of relay L^3 , and the winding of relay K^3 to terminal o . Relay K^3 then continues energized by its stick circuit which is controlled by contact 38 of relay P^3 . Relay K^3 , upon becoming energized, causes lamp e^3 to become lighted by its circuit passing from terminal B, through contact 41 of relay K^3 , and lamp e^3 to terminal o . Relay K^3 , upon becoming energized, also causes relay L^3 to become energized in the reverse direction by its reverse control circuit passing from terminal B, through contact 40^a of relay K^3 , and the reverse control winding of relay L^3 to terminal o .

When, now, the first train upon starting to leave stretch N enters section C—A—G, relay I^2 becomes energized by its pick-up circuit passing from terminal B, through contact 22 of relay R^2 , contact 23 of relay r^2 , and the winding of relay I^2 to terminal o .

Relay r^2 , after a brief period, permits its contact 23 to open but relay I^2 then continues energized by its stick circuit passing from terminal B, through contact 22 of relay R^2 , contact 24 of relay I^2 , and the winding of relay I^2 to terminal o . Relay I^2 , upon becoming energized, completes at its contact 18 the circuit for relay Y^2 passing from terminal B, through contact 16 of relay R^4 , contact 17 of relay R^2 , contact 18 of relay I^2 , and the winding of relay Y^2 to terminal o . Relay Y^2 , upon becoming energized, closes its contacts 29 and 33. With contact 29 closed, relay y^2 becomes energized by its circuit passing from terminal B, through contact 29, and the winding of relay y^2 to terminal o .

Relay y^2 , on account of its slow pick-up characteristic, does not at once open its contact 32, and hence a circuit for code transmitter E^2 is closed for a brief period, passing from terminal B, through contact 32 of relay y^2 , contact 33 of relay Y^2 , and code transmitter E^2 to terminal o . Code transmitter E^2 now supplies conductors 8 and 9 for a brief period with current of the second code, which causes selector S^2 to close its contact 35 for a corresponding brief period.

With contact 35 of selector S^2 closed, relay P^1 becomes energized by its circuit passing from terminal B, through contact 35 of selector S^2 , wire 42, contact 43^a of relay Q^1 , and the winding of relay P^1 to terminal o . Relay P^1 , upon becoming energized, opens at its contact 38 the stick circuit already traced for relay K^1 which then becomes deenergized, closing its contact 44 and so completing a stick circuit for relay P^1 passing from terminal B, through contact 44 of relay K^1 , contact 45 of relay P^1 , and the winding of relay P^1 to terminal o . Relay K^1 , upon becoming deenergized, causes relay L^1 to again be energized by its normal control circuit which has already been traced. Relay L^1 then again closes its contact 37^a. Relay K^1 , upon becoming deenergized, also opens, at its contact 41, the lighting circuit for lamp e^1 which is thereby extinguished. Relay P^1 , upon becoming energized, causes relay Q^1 to be energized in the reverse direction by its reverse control circuit passing from terminal B, through contact 46^a of relay P^1 , and the reverse control winding of relay Q^1 to terminal o . Relay Q^1 then opens its contact 43^a and closes its contact 43^b.

When, now, the second westbound train enters section C—A—G, causing code transmitter E^2 to again supply conductors 8 and 9 with current of the second code, selector S^2 again closes its contact 35, now completing the pick-up circuit for relay P^2 passing from terminal B, through contact 35 of selector S^2 , wire 42, contact 43^b of relay Q^1 , contact 43^a of relay Q^2 , and the winding of relay P^2 to terminal o . Relay P^2 , upon becoming energized, opens, at its contact 38, the stick

circuit for relay K^2 which then becomes de-energized. Relay P^2 then continues energized by its stick circuit passing from terminal B, through contact 44 of relay K^2 , contact 45 of relay P^2 , and the winding of relay P^2 to terminal o. Relay P^2 , upon becoming energized, causes relay Q^2 to be energized in the reverse direction by its reverse control circuit passing from terminal B, through contact 46^a of relay P^2 , and the reverse control winding relay Q^2 to terminal o. Relay K^2 , upon becoming deenergized, opens, at its contact 41, the lighting circuit for lamp e^2 which is thereby extinguished. Relay K^2 becoming deenergized causes relay L^2 to be again energized by its normal control circuit as already traced. Relay L^2 then opens its contact 37^b and closes its contact 37^a.

When the third westbound train enters section C—A—G, causing code transmitter E^2 to again supply current of the second code to conductors 8 and 9, selector S^2 again closes its contact 35 for a brief period, causing relay P^3 to this time be energized by its pick-up circuit passing from terminal B, through contact 35 of selector S^2 , wire 42, contacts 43^b of relays Q^1 and Q^2 , contact 43^a of relay Q^3 , and the winding of relay P^3 to terminal o. Relay P^3 , upon becoming energized, opens, at its contact 38, the stick circuit for relay K^3 which then becomes deenergized. Relay P^3 now continues energized by its stick circuit passing from terminal B, through contact 44 of relay K^3 , contact 45 of relay P^3 , and the winding of relay P^3 to terminal o. Relay P^3 , upon becoming energized, causes relay Q^3 to be energized in the reverse direction by its reverse control circuit which is controlled by contact 46^a of relay P^3 . Relay K^3 , upon becoming deenergized, opens its contact 41 thus causing lamp e^3 to be extinguished. Relay K^3 , upon becoming deenergized, also causes relay L^3 to again be energized in the normal direction by its normal control circuit which is controlled by contact 40^b of relay K^3 .

If, now, a fourth westbound train enters stretch N, causing code transmitter E^4 to again supply conductors 8 and 9 with current of the first code, relay K^1 again becomes energized by its pick-up circuit as already traced. Relay K^1 , upon becoming energized, breaks the stick circuit already traced for relay P^1 which then becomes deenergized, and relay K^1 then continues energized by its stick circuit formerly traced. Relay K^1 now causes lamp e^1 to be lighted and relay L^1 to be energized in the reverse direction as already described.

The operation of lamps e^4 , e^5 and e^6 , as controlled by eastbound trains through selectors S^3 and S^4 , is exactly similar to that which I have just described for lamps e^1 , e^2 and e^3 as controlled by westbound trains through selectors S^1 and S^2 .

From the foregoing description and the accompanying drawings, it is clear that apparatus embodying my invention comprises means for checking trains into and out of any given territory and for indicating at any time the number of trains within such territory. Although, for the sake of simplicity, I have shown apparatus for indicating only three trains at a time for a given stretch of track, it should be noted that additional indicators can be provided for indicating additional trains, and that for controlling each such additional indicator, a group of four additional relays such, for example, as relays K^3 , L^3 , P^3 and Q^3 would then be required.

Although I have herein shown and described only one form of train indicating apparatus embodying my invention, it is understood that various changes and modifications may be made therein within the scope of the appended claims without departing from the spirit and scope of my invention.

Having thus described my invention, what I claim is:

1. In combination, a railway passing siding connected at each of its ends with a main track by means of a track switch, a track circuit for said siding including a track relay, a switch track circuit including the first of said switches and a track relay, an approach track circuit adjoining said switch track circuit and including a track relay, a slow-release relay controlled by a front contact of said switch track relay and by a front contact of said approach track relay, a stick relay, a pick-up circuit for said stick relay controlled by a front contact of said slow-release relay and by a back contact of said switch track relay, a stick circuit for said stick relay controlled by a back contact of said switch track relay, an indication means, means controlled by a back contact of said stick relay and by a back contact of said siding track relay as well as by a front contact of said switch track relay for energizing said indication means, a second switch track circuit including the second of said switches, and means controlled by said second switch track circuit for deenergizing said indication means.

2. In combination, a stretch of railway track, a detector track circuit for said stretch including a track relay, an approach track circuit for said stretch including a track relay, a second approach track circuit between said first approach track circuit and said detector circuit, a slow-release relay controlled by said second approach track relay and by said first approach track relay, a stick relay, a pick-up circuit for said stick relay controlled by said slow-release relay and by said second approach track relay, a stick circuit for said stick relay controlled by said

second approach track relay, indication means, and means controlled by said stick relay and by said detector track relay for controlling said indication means.

- 5 3. In combination, a stretch of railway track, a detector track circuit for said stretch including a track relay, an approach track circuit for said stretch including a track relay, a second approach track circuit between 70
10 said first approach track circuit and said detector track circuit, a slow-release relay controlled by said second approach track relay and by said first approach track relay, a stick relay, a pick-up circuit for said stick 75
15 relay controlled by said slow-release relay and by said second approach track relay, a stick circuit for said stick relay controlled by said second approach track relay, indication means, and means controlled by said stick 80
20 relay and by said detector track relay as well as by a front contact of said second approach track relay for controlling said indication means.

4. In combination, a stretch of railway 90
25 track, a first and a second stick relay, a first and a second polarized relay, traffic controlled means for energizing said first stick relay when a train enters said stretch while a normal contact of said first polarized 95
30 relay is closed, a stick circuit for said first stick relay controlled by a back contact of said second stick relay, a normal control circuit for said first polarized relay controlled by a back contact of said first stick relay, a reverse 100
35 control circuit for said first polarized relay controlled by a front contact of said first stick relay, traffic controlled means for energizing said second stick relay when a train leaves said stretch while a normal contact of 105
40 said second polarized relay is closed, a stick circuit for said second stick relay controlled by a back contact of said first stick relay, a normal control circuit for said second polarized relay controlled by a back contact of said 110
45 second stick relay, a reverse control circuit for said second polarized relay controlled by a front contact of said second stick relay, an indication means controlled by said first stick relay, and an indication means controlled by a reverse contact of said first polarized relay and by a reverse contact of said second polarized relay.

5. In combination, a stretch of railway 115
55 track adapted to contain a predetermined number of cars, a series of relays corresponding in number with the number of cars said stretch is adapted to contain and operated successively by cars upon entering said stretch, and means controlled by the last relay of said series for indicating when said stretch contains such predetermined number of cars.

6. In combination, a stretch of railway 120
65 track adapted to contain a predetermined number of cars, a series of relays operated in

a predetermined order by cars upon entering said stretch, such of said relays as are later in their order of operation being dependent upon the operation of relays having an earlier order of operation, and means controlled by the relay last in its order of operation for indicating when said stretch contains such predetermined number of cars.

7. In combination, a stretch of railway track adapted to contain a predetermined number of cars, a series of main relays operable in a predetermined order by cars upon entering said stretch, a series of auxiliary relays, one associated with each of said main relays and each adapted to condition a succeeding main relay for operation by a car upon the operation of the main relay with which it is associated by a preceding car, and a signal controlled by the last of said series of auxiliary relays for indicating when said stretch contains such predetermined number of cars.

8. In combination, a stretch of railway track adapted to contain a predetermined number of cars, means for indicating when said stretch contains said predetermined number of cars, a first normally energized relay controlled by the last car of said predetermined number of cars for controlling said indication means, a second normally energized relay controlled by a preceding car for controlling said first normally energized relay, and a third normally energized relay controlled by a car preceding said second-mentioned car for controlling said second normally energized relay.

9. In combination, a stretch of railway track, a first stick relay, a second stick relay, a pick-up circuit for said first stick relay controlled by traffic entering said stretch, a stick circuit for said first stick relay controlled by said second stick relay, a pick-up circuit for said second stick relay controlled by traffic leaving said stretch, a stick circuit for said second stick relay controlled by said first stick relay, and a traffic governing device controlled by said second stick relay.

10. In combination, a stretch of railway track, an arrival relay controlled by traffic entering said stretch, a departure relay controlled by traffic leaving said stretch, a first stick relay, a second stick relay, a pick-up circuit for said first stick relay controlled by said arrival relay, a stick circuit for said first stick relay controlled by said second stick relay, a pick-up circuit for said second stick relay controlled by said departure relay, a stick circuit for said second stick relay controlled by said first stick relay, and a traffic governing device controlled by said second stick relay.

11. In combination, a stretch of railway track adapted to contain a predetermined number of cars, an arrival relay operable by cars entering said stretch, a departure relay 130

operable by cars leaving said stretch, a first stick relay, a second stick relay, a pick-up circuit for said first stick relay controlled by said arrival relay, a stick circuit for said 5 first stick relay controlled by said second stick relay, a pick-up circuit for said second stick relay controlled by said departure relay, a stick circuit for said second stick relay controlled by said first stick relay, and means 10 controlled by said second stick relay for indicating when said stretch contains said predetermined number of cars.

In testimony whereof I affix my signature.

PAUL P. STOKER.
